CLAIM

The ornamental design for an electronic device with transitional graphical user interface, as shown and described.

DESCRIPTION

1. Electronic device with transitional graphical user interface

2. Electronic device with transitional graphical user interface

1.1: Front view of the electronic device with transitional graphical user interface showing a first image;

1.2: Front view thereof showing a second image;

1.3: Front view thereof showing a third image;

1.4: Front view thereof showing a fourth image;

2.1: Front view of the electronic device with transitional graphical user interface showing a first image;

2.2: Front view thereof showing a second image;

2.3: Front view thereof showing a third image;

2.4: Front view thereof showing a fourth image;

The broken line showing of an electronic device with transitional graphical user interface is included for the purpose of illustrating portions of the article and forms no part of the claimed design.

The appearance of the transitional image sequentially transitions between the images shown in reproductions 1.1-1.4 and 2.1-2.4. The process or period in which one image transitions to another image forms no part of the claimed design.

1 Claim, 8 Drawing Sheets

○

1.4

3. The quotient of two numbers is 1. Their sum is 6. What are the two numbers?

1. Let's denote the two numbers as x and y.

2. According to the problem, the quotient of x and y is 1, which can be expressed as $x/y = 1$.

3. Their sum is given as 6, so we have the equation $x + y = 6$.

4. From the first equation, we can solve for x by multiplying both sides by y, which gives us $x = y$.

5. Now we substitute $x = y$ into the second equation: $y + y = 6$.

6. Combining like terms, we get $2y = 6$.

7. Dividing both sides by 2, we find $y = 3$.

8. Since $x = y$, we have $x = 3$ as well.

9. Therefore, the two numbers are $x = 3$ and $y = 3$.

So the two numbers are both 3.

QuestionAI

3. The quotient of two numbers is 1. Their sum is 6. What are the two numbers?

- 1. Let's denote the two numbers as x and y .
  - 2. According to the problem, the quotient of x and y is 1, which can be expressed as $x/y = 1$.
  - 3. Their sum is given as 6, so we have the equation $x + y = 6$.
  - 4. From the first equation, we can solve for x by multiplying both sides by y , which gives us $x = y$.
  - 5. Now we substitute $x = y$ into the second equation: $y + y = 6$.
  - 6. Combining like terms, we get $2y = 6$.
  - 7. Dividing both sides by 2, we find $y = 3$.
  - 8. Since $x = y$, we have $x = 3$ as well.
  - 9. Therefore, the two numbers are $x = 3$ and $y = 3$.
- So the two numbers are both 3.
